DESIGN FOR A FIRE EXTINGUISHER OR SIMILAR ARTICLE

Stewart Boal, Winnetka, Ill., assignor to Randolph Laboratories, Inc., Chicago, Ill., a corporation of Illinois

Application September 13, 1946, Serial No. 133,280

Term of patent 14 years

(Cl. D16—2)

To all whom it may concern:

Be it known that I, Stewart Boal, a citizen of the United States, residing at Winnetka, in the county of Cook and State of Illinois, have invented a new, original, and ornamental Design for a Fire Extinguisher or Similar Article, of which the following is a specification, reference being had to the accompanying drawing, forming a part thereof.

In the drawing:

Fig. 1 is a view in front elevation of a fire extinguisher or similar article embodying my new design;

Fig. 2 is a view in side elevation thereof; and

Fig. 3 is a top plan view thereof.

I claim:

The ornamental design for a fire extinguisher or similar article, substantially as shown.

STEWART BOAL.
